UNITED STATES PATENT OFFICE.

BÖRRE H. BÖRRESON, OF MINNEAPOLIS, MINNESOTA.

CARD AND TAG HOLDER.

Application filed June 13, 1921. Serial No. 477,159.

To all whom it may concern:

Be it known that I, BÖRRE H. BÖRRESON, a citizen of the United States, resident of Minneapolis, county of Hennepin, State of Minnesota, have invented certain new and useful Improvements in Card and Tag Holders, of which the following is a specification.

The object of my invention is to improve the card and tag holder shown in my pending application for Letters Patent of the United States, Serial No. 315,121, filed August 4, 1919, provision being made herein for sealing the holder to prevent the unauthorized removal of the card or tag and also to provide means for excluding moisture and dirt from the interior of the holder.

The invention consists generally in various constructions and combinations, all as hereinafter described and particularly pointed out in the claims.

In the accompanying drawings forming part of this specification,

Figure 1 is a plan view of a card or tag holder embodying my improvement,

Figure 2 is a sectional view on the line 2—2 of Figure 1,

Figure 3 is an end rear view of the holder, showing the manner of sealing the card therein,

Figure 4 is a sectional view on the line 4—4 of Figure 3,

Figure 5 is a rear end view of a holder showing a cap or cover for excluding moisture from the interior of the holder,

Figure 6 is a view of the cap or cover detached from the holder,

Figure 7 is a sectional view on the line 7—7 of Figure 5,

Figure 8 is a detail view showing a modified manner of inserting the sealing wire in the holder,

Figure 9 is a rear end view showing a modification in the arrangement of the sealing means,

Figure 10 is a sectional view on the line 10—10 of Figure 9,

Figure 11 illustrates the blank or plate from which the holder is formed, after the first impression of the die,

Figure 12 is a similar view after the first impression, showing the mica sheet in position.

Figure 13 is a view illustrating the completed holder or after the second impression of the die.

In the drawing, 2 represents a plate or sheet of suitable metal, preferably aluminum, having a depressed portion 3 formed by the application of a die thereto to provide a recess for the reception of the card or tag placed in the holder that is inserted through the slot 4 formed in one end wall of the recess when the die is applied to form such recess. This slot 4 extends transversely through the end wall of the recess and permits the card or tag to be easily inserted or removed. A rib 6^a is preferably formed between the recess 3 and the edge of the plate and will serve to exclude dust and moisture from the holder. A flange 7 is arranged to overhang the slot 4 and serve as a guard therefor and for the end of the tag and said flange has holes 8 therein adapted to register with holes in the rib 6^a through which a loop or wire 9 for the seal is inserted. I prefer to provide a slot in the outer wall of the rib 6^a to receive the loop of the wire, while the inner walls of the rib 6^a have holes through which the ends of the wire are inserted. The bottom 3 of the holder is preferably provided with a recess 10 of suitable size and shape to receive the seal so that it can lie flat against the back of the holder and substantially flush with the surface thereof. Evidently when this seal is in place and the tag or card 10^a has been inserted in the holder, it will be impossible to remove it without cutting the wire or damaging the card and this cannot be done without detection. Only a narrow gap is provided between the flange and the rib 6^a for the insertion of the card 10^a into the holder and this flange will thus so nearly close the opening for the insertion of the card that dust and moisture will practically be excluded from the holder.

In Figures 5, 6 and 7, 14 represents a plate, preferably of metal, having a flange 15 that is adapted to fit the end of the holder and cover the seal and the opening in the holder leading to the card. The plate is provided with holes 16 adapted to register with similar holes 17 in the holder into which a suitable securing means may be inserted. When this device is in place, the end of the holder

and the gap leading to the card will be concealed and thoroughly protected from dust and moisture arising from the accumulation of ice or snow on the holder or when the card is in use in a rain storm. Access to the holder and seal may be obtained at any time by removing the means for fastening the plate to the holder.

In Figures 9 and 10 I have shown a modification which consists in providing openings 18 in the rear wall of the holder leading to the space occupied by the identification card and into these openings sealing wax may be run to spread out on the card between it and the wall of the holder and form a seal which, when broken, would indicate to the observer that someone had been tampering with the card and holder.

Upon the first operation of the die and the formation of the depressed portion 3 in the plate, the edges of the blank are folded to form a vertical flange 19 between which and the recess in the blank a shelf or step 20 is provided whereon the sheet of transparent material, such as mica 21, is placed. This sheet covers the recess and the card or tag 10^a and protects it from damage by wet or other causes, while at the same time permitting free inspection of the card and the printed matter or writing thereon.

When the transparent sheet has been put in place, the flange 19 is rolled over upon it by the second operation of the die to the position shown in Figure 13, where the edges 35 of the sheet are completely concealed and held firmly in the holder, so that removal is impossible without breaking the plate or otherwise damaging it.

It will be noted that the frame is composed of a single sheet of metal, preferably aluminum, folded through a series of impressions to form a complete frame or holder for the license or identification card, that the card will be protected from dust and moisture, 45 and when the seal is inserted in the holder it will be impossible for any one to remove or tamper with the card without detection.

I claim as my invention:

50 1. A card or tag holder comprising a metallic plate having a depressed portion forming a recess for the reception of the card or tag and a slot in one wall of said recess through which the card may be inserted, said plate having a flanged portion encircling said recess, said flange having a rib formed therein on which a transparent plate is seated, and said flange having a part that is folded inwardly over said transparent plate for holding it in position over the card or tag, and a sealing means adapted to prevent removal of the card through said slot.

2. A card or tag holder comprising a plate having a seat for a card or tag and an opening through which the card is in-

serted to its seat, said plate also having a flange and a seat for a transparent plate arranged over said card, the edges of said flange being folded inwardly over the edges of said plate, and a wire sealing means 70 adapted to prevent removal of the card through said opening.

3. A card or tag holder comprising a plate having a seat for a card or tag and an opening through which the card is inserted to its seat, said plate also having a flange and a seat for a transparent plate arranged over said card, the edges of said flange being folded inwardly over the edges of said plate, a flange overhanging the opening through which the card is inserted, and a seal passing through said overhanging flange and bridging said opening to prevent removal of the card therethrough.

4. A card or tag holder comprising a plate having a depressed portion forming a recess for the reception of the card or tag, and a slot in the wall of said recess through which the card may be inserted, a flange overhanging said slot and a sealing means 80 arranged to prevent the removal of the card through said slot, said sealing means comprising means bridging said slot and having a lock thereon.

5. A card or tag holder comprising a plate having a depressed portion forming a recess for the reception of the card or tag, and a slot in the wall of said recess through which the card may be inserted, a flange overhanging said slot, said flange and the wall of said holder on the opposite side of said slot from said flange having holes therein, and a wire seal fitting said holes and bridging said slot and having a suitable lock.

6. A card or tag holder comprising a plate having a depressed portion forming a recess for the reception of the card or tag, and a slot in the wall of said recess through which the card may be inserted, a seal arranged to bridge said slot and prevent the removal of said card, and a guard plate arranged to cover said seal and slot.

7. A card or tag holder comprising a plate having a depressed portion forming a recess for the reception of a card or tag, and an opening through which the card may be inserted, said plate having a flanged portion encircling said recess, said flange having a rib formed therein on which a transparent plate is seated, and said flange having a part that is folded inwardly over said transparent plate for holding it in position over the card or tag, and a sealing means arranged to prevent removal of the card through said opening.

8. A card or tag holder comprising a plate having a seat for a card or tag and an opening through which the card is inserted to its seat, said plate also having a

flange and a seat for a transparent plate sealing means adapted to prevent removal 15
arranged over said card, the edges of said flange being folded inwardly over the edges of said plate, and a guard plate mounted 5 to cover and conceal the opening leading to said card.

9. A card or tag holder comprising a plate having a seat for a card or tag and an opening through which the card is inserted in its seat, said plate also having a flange and a shelf for a transparent plate arranged beyond the edges of said card, the edges of said flange being folded inwardly over the edges of said plate, and a

10. A card or tag holder comprising a plate having a depressed portion forming a recess for the reception of the card or tag, and a slot through which the card may be 20 inserted, said plate having a flanged portion adapted to be turned upwardly and inwardly upon a transparent plate that is seated over said card, and means bridging said slot for sealing said card in said recess. 25

In witness whereof, I have hereunto set my hand this 9th day of June, 1921.

BÖRRE H. BÖRRESON.
